UNITED STATES PATENT OFFICE.

JOHN W. CANRIKE, OF COLDWATER, MICHIGAN.

FLYING-MACHINE.

1,234,727.

Specification of Letters Patent. Patented July 31, 1917.

Application filed October 9, 1916. Serial No. 124,679.

To all whom it may concern:

Be it known that I, JOHN W. CANRIKE, a citizen of the United States, and a resident of Coldwater, in the county of Branch, State 5 of Michigan, have invented certain new and useful Improvements in Flying-Machines, of which the following is a specification, reference being had to the accompanying drawings.

10 My invention relates to flying machines and is particularly applicable to aeroplanes. It is one of the principal objects of my invention to provide an improved driving means by the use of which the craft upon 15 which it is mounted can be caused to rise from the ground in a very short space without a long preliminary run, and which in turn shall be capable of descending safely within a like limited space. To this end, it is one of the objects of my invention to provide a new and improved form and arrangement of driving connections between the engine and the propeller or propellers. It is another object of my invention to provide 20 for swinging the propeller means vertically relative to the framework of the craft, suitable means being provided for accomplishing this result readily and easily while at the same time holding the propeller firmly 25 in position relative to the frame as may be desired. It is another object of my invention to improve devices of this type in sundry details hereinafter pointed out. The preferred means by which I have accomplished my several objects are illustrated in 30 the drawings and are hereinafter specifically described. That which I believe to be new and desire to cover by this application is set forth in the claims.

35 In the drawings:—

Figure 1 is a vertical cross-section through a portion of an aeroplane showing my improvements;

Fig. 2 is a horizontal section taken substantially on line 2—2 of Fig. 1;

Fig. 3 is an enlarged detail, being a longitudinal vertical section through the walking-beam by which the propeller is held in position relative to the frame, the chain by 50 which connection is made to the controlling gearing being shown removed from its connection with said gearing;

Fig. 4 is a vertical cross-section through the controlling gearing showing the engagement of the chain therewith;

Fig. 5 is a vertical cross-section through

the supporting shaft adjacent to the controlling gearing showing the provision of a braking means for said gearing;

Fig. 6 is a top view of a section of the 60 chain;

Fig. 7 is a side view of the parts shown in Fig. 6; and

Fig. 8 is a vertical cross-section taken on line 8—8 of Fig. 6.

Referring to the several figures of the drawings in which corresponding parts are indicated by the same reference characters,—

10 indicates the framework of an aeroplane provided with planes 11—12 of any suitable type and provided with one or more supporting wheels 13. A horizontal shaft 14 is revolubly supported across the front of the framework between upright bars 15—16 of said framework, said shaft being provided with a bevel gear 17 which meshes with a bevel gear 18 which is connected by means of a shaft 19 with a motor 20 of any suitable type. In the preferred construction, a clutch 21 of any suitable type is provided adapted to be operated by a lever 22 for throwing the motor 20 into and out of operative connection with the gear 17.

Revolubly mounted upon the shaft 14 so as to swing readily thereabout is a yoke 23 which provides a bearing 24 for the rear end portion of a shaft 25, upon which shaft is fixedly mounted a gear 26 meshing with the gear 17. The bearing 24 is of any suitable type to take both the side pressure and the end thrust of the shaft 25, as hereinafter described. The forward end of the shaft 25 is supported relative to the yoke 23 and the shaft 14 by means of laterally-extending ties 27—28 and trussed horizontal ties 29—30, the ties 27—28 being revolubly connected at their rear ends to the shaft 14. The ties 27, 28, 29 and 30 are all connected at their forward ends to a bearing member 31 within which the shaft 25 is revolubly mounted. A propeller 32 of any suitable type is fixed upon the forward end of the shaft 25.

Fixedly mounted between the frame-bars 15—16 is a bar or shaft 33 upon which is revolubly mounted a gear or drum 34 to which is fixedly connected a hand-wheel 35 by which the drum or gear is adapted to be turned about the shaft 33. A friction ring 36 is fixedly connected with the gear or drum 34. A sleeve 37 is fixedly mounted upon the bar or shaft 33 adjacent to the friction ring 36 provided with an arm 38 extending there-

from. A friction band 39 surrounds the friction ring 36, one end of the band 39 being fixedly connected to the arm 38, and the other end of said band being adjustably connected to said arm 38 by means of a lever 40 and a link 41. As will be readily understood, when the lever 40 stands in the position shown in Fig. 5 the band 39 serves to hold the ring 36 and the drum 34 against rotation upon the shaft 33. When the lever 40 is moved a short distance to the right in said Fig. 5, the band 39 is released from the ring 36 permitting the said ring 36 and the drum 34 to rotate freely relative to said shaft.

42 indicates a walking-beam pivotally connected by means of a pin 43 with the bearing member 31, being adjustably connected at its upper end portion with the drum 34 and the hand-wheel 35. This adjustable connection between the walking-beam 42 and the drum 34 is effected by means of a chain 44 which extends about the drum 34 and is connected at its ends to the said walking-beam, being preferably maintained fairly taut so as to provide very little lost motion, if any, in the connection between the hand-wheel 35 and the walking-beam. The several links of the chain 44 are so formed and so connected with each other as to provide ample lateral flexibility so as to permit the chain to be wound spirally about the drum 34 as shown in Fig. 4. The transversely-extending portion 45 of each of the links of the chain is bent into a loop, as is best shown in Fig. 8, whereby such portions of the several links are adapted to engage the laterally-extending bars or pins 46 of the gear or drum 34. With the chain 44 extending tightly about the drum 34 in a single spiral loop thereabout, the chain is held against slippage relative to the drum, serving thus to hold the walking-beam against adjustment. The arrangement is such that a very considerable amount of force must be applied through the walking-beam 42 to rotate the drum 34, even without the application of the braking device to such drum, while at the same time force can be applied through the hand-wheel to very good advantage for moving the walking-beam longitudinally of itself.

In the use of my improved construction, whenever it is desired to cause the craft to move quickly upward or downward, the propeller 32 and its shaft 25 are moved quickly in the desired direction for effecting this result. Before the start for a flight from the ground, the shaft 25 and propeller 32 will be moved upward relative to the framework so as to cause the propeller to lift sharply upon the forward end of the framework, causing the machine to rise quickly from the ground within a very small space. 65 When the propeller is held in elevated posi-

tion relative to the framework, not only does the propeller lift upon the forward end of the frame, but it also has a tendency to condense the atmosphere underneath the planes between the planes and the ground, producing an additional tendency to raise the craft quickly. Whenever in starting a flight or in flying close to the ground it is or may be desired to shift the propeller quickly relative to the framework, the operator preferably maintains the position of the propeller as desired through his hold upon the hand-wheel 35, but whenever it is desirable to do so the operator can set the propeller at the desired position and lock it against adjustment by the use of the braking mechanism.

It will be understood that in an operative construction embodying my improvements suitable means will be provided as is usual in flying machines for controlling the machine, such as horizontal rudders, vertical rudders, and plane-warping mechanisms. Any suitable type of automatically-acting stabilizers may be used as desired.

While I have shown a craft provided with only a single propeller, it will be understood that any suitable number of propellers may be employed as desired without departing from my invention. It will also be understood that I do not wish to restrict myself to the arrangement for driving the gear 17 as shown in the drawings, the engine 20 and its connecting means being given any suitable arrangement as may be desired by the designer of any particular craft.

So far as I am aware, I am the first in the art to provide for controlling the position of an adjustable propeller by means of a rigid bar or link, such as the walking-beam 42, having an operative pivotal connection at one end with the propeller and being itself held in adjusted position by means of a flexible connector secured at its ends to the link and having its intermediate portion extending tightly about a drum revolvably mounted in suitable position, the flexible connector serving to hold the link in close proximity to the drum. In view of the great utility of this form of controlling device for this purpose, being responsive to the application of a slight external force for turning the drum while at the same time being adapted to resist strongly any tendency of the propeller to shift its position independently of the operator, I wish to claim this expedient broadly in the combination shown, and my claims are to be construed accordingly.

What I claim as my invention and desire to secure by Letters Patent, is—

1. In a flying-machine, the combination of a framework, an engine mounted on said framework, a propeller operatively connected with said framework and adapted to

- be adjustable angularly relative thereto, connections between said propeller and said engine effective at any desired adjustment of said propeller for rotating the propeller, a rigid link having an operative pivotal connection at one end with the propeller, a drum rotatably mounted on said framework in spaced relation to the axis about which the propeller is adjustable, and a flexible connector secured at its ends to the link and extending at an intermediate point tightly about said drum serving to hold the link in position adjacent to the drum and serving to hold said link in adjusted position relative to the drum.
- 5 2. In a flying machine, the combination of a framework, an engine mounted on said framework, a propeller operatively connected with said framework and adapted to be swung vertically about a horizontal transverse axis relative to said framework, driving connections between said propeller and said engine effective at any desired vertical adjustment of the propeller, a bar operatively connected at one end with said propeller and extending obliquely backward to a point above the axis about which said propeller is adapted to be swung, and means comprising a chain adjustably connected to 10 said framework for shifting said bar.
- 20 3. In a flying machine, the combination of a framework, a shaft mounted thereon extending transversely thereof, a second shaft adapted to be swung about said first-named shaft, bevel gears operatively connecting said two shafts, a propeller fixedly connected with the free end portion of said second shaft and adapted to be moved vertically with said shaft about said first-named shaft, a bar operatively connected with said second shaft near its forward end, a drum revolvably mounted on said framework, and a flexible connector passing about said drum and connected at its 25 ends to said bar for adjusting the vertical position of said shaft and said propeller.
- 25 4. In a flying machine, the combination of a framework, an engine mounted on said framework, a propeller operatively connected with said framework and adapted to be adjusted angularly relative thereto, connections between said propeller and said engine effective at any desired adjustment of said propeller for rotating the propeller, a bar operatively connected with said propeller, a drum gear revolvably mounted on said framework in a single spiral loop and connected at its ends to said bar, and a hand-wheel operatively connected with said drum gear for rotating said gear for adjusting the angle of said propeller.
- 30 5. In a flying machine, the combination of a framework, an engine mounted on said framework, a propeller operatively connected with said framework and adapted to be adjusted angularly relative thereto, connections between said propeller and said engine effective at any desired adjustment of said propeller for rotating the propeller, a bar operatively connected at its forward end with said propeller, a drum gear revolvably mounted on said framework, a chain passing about said drum gear in a single spiral loop and connected at its ends to said bar, and a hand-wheel operatively connected with said drum gear for rotating said drum for adjusting the angle of said propeller, and means for locking said drum against rotation for holding the propeller in fixed 35 adjusted position.
- 35 6. In a flying machine, the combination of a framework, an engine mounted on said framework, a propeller operatively connected with said framework and adapted to be adjusted angularly relative thereto, connections between said propeller and said engine effective at any desired adjustment of said propeller for rotating the propeller, a bar operatively connected at its forward end with said propeller, a drum gear revolvably mounted on said framework on a transversely-extending axis and having transversely-extending bars arranged about its periphery, a chain extending tightly about said drum gear in a spiral loop thereabout and connected at its ends to said bar, and a hand-wheel operatively connected with said drum gear for rotating the gear for adjusting the angle of said propeller.
- 40 7. In a flying machine, the combination of a framework, a shaft revolvably mounted on said framework extending transversely thereof, a yoke having its end portions revolvably mounted on said shaft, a second shaft extending forward from said first-named shaft having its rear end portion revolvably mounted in a suitable bearing in said yoke, a bearing for the forward end portion of said second shaft, means connecting said second-named bearing with said yoke, diagonally-disposed ties connected at their forward ends with said second-named bearing and pivotally connected at their rear ends with said first-named shaft, bevel 45 gear for adjusting the angle of said propeller.
- 45 8. In a flying machine, the combination of a framework, an engine mounted on said framework, a propeller operatively connected with said framework and adapted to be adjusted angularly relative thereto, connections between said propeller and said engine effective at any desired adjustment of said propeller for rotating the propeller, a bar operatively connected with said propeller, a drum gear revolvably mounted on said framework, a chain passing about said drum gear in a single spiral loop and connected at its ends to said bar, and a hand-wheel operatively connected with said drum gear for rotating said gear for adjusting the angle of said propeller.
- 50 9. In a flying machine, the combination of a framework, an engine mounted on said framework, a propeller operatively connected with said framework and adapted to be adjusted angularly relative thereto, connections between said propeller and said engine effective at any desired adjustment of said propeller for rotating the propeller, a bar operatively connected with said propeller, a drum gear revolvably mounted on said framework, a chain passing about said drum gear in a single spiral loop and connected at its ends to said bar, and a hand-wheel operatively connected with said drum gear for rotating said gear for adjusting the angle of said propeller.
- 55 10. In a flying machine, the combination of a framework, an engine mounted on said framework, a propeller operatively connected with said framework and adapted to be adjusted angularly relative thereto, connections between said propeller and said engine effective at any desired adjustment of said propeller for rotating the propeller, a bar operatively connected with said propeller, a drum gear revolvably mounted on said framework, a chain passing about said drum gear in a single spiral loop and connected at its ends to said bar, and a hand-wheel operatively connected with said drum gear for rotating said gear for adjusting the angle of said propeller.
- 60 11. In a flying machine, the combination of a framework, an engine mounted on said framework, a propeller operatively connected with said framework and adapted to be adjusted angularly relative thereto, connections between said propeller and said engine effective at any desired adjustment of said propeller for rotating the propeller, a bar operatively connected with said propeller, a drum gear revolvably mounted on said framework, a chain passing about said drum gear in a single spiral loop and connected at its ends to said bar, and a hand-wheel operatively connected with said drum gear for rotating said gear for adjusting the angle of said propeller.
- 65 12. In a flying machine, the combination of a framework, an engine mounted on said framework, a propeller operatively connected with said framework and adapted to be adjusted angularly relative thereto, connections between said propeller and said engine effective at any desired adjustment of said propeller for rotating the propeller, a bar operatively connected with said propeller, a drum gear revolvably mounted on said framework, a chain passing about said drum gear in a single spiral loop and connected at its ends to said bar, and a hand-wheel operatively connected with said drum gear for rotating said gear for adjusting the angle of said propeller.

eled gears operatively connecting said two shafts, a propeller fixedly connected with the free end portion of said second shaft and adapted to be adjustable vertically with 5 said shaft about said first-named shaft, a bar operatively connected with said second shaft near its forward end, a drum revo-

lubly mounted on said framework, and a flexible connector passing tightly about said drum and connected at its ends to said bar 10 for adjusting the vertical position of said shaft and said propeller.

JOHN W. CANRIKE.
